CONTAINER CLOSURE

Robert Billeter, Burlingame, and John W. Giffin,
San Francisco, Calif.

Application February 14, 1940, Serial No. 318,856

2 Claims. (Cl. 220—54)

This invention relates to improvements in container closures and has particular reference to means for opening the end of a sealed can or other similar container.

The principal object of this invention is to provide means for removing the end of the can through the employment of a tear-strip formed within the end of the can in counterdistinction to the use of a tear-strip formed on the side of a can.

A further object of the invention is to provide a can end which will prevent particles of metal or other foreign matter from entering the contents of the can.

A further object of the invention is to provide a tear-strip opening can wherein the contents of the can will not be spilled during the opening operation.

A further object of the invention is to produce a device of this character which may be applied to any standard form of can or container without materially altering its construction, and a device which may be incorporated in the construction of the completed can without adding materially to its cost.

A further object of the invention is to produce a device of this character which will not slow up production, and one which will conform to all standard sanitary regulations.

A further object of the invention is to provide means for guiding the tear-strip during the tearing operation.

Other objects and advantages will be apparent during the course of the following description.

In the accompanying drawing forming a part of this specification and in which like numerals are employed to designate like parts throughout the same,

Fig. 1 is a top plan view of a can constructed in accordance with our invention;

Fig. 2 is a cross sectional view on an enlarged scale taken on the line 2—2 of Fig. 1, looking in the direction of the arrows;

Fig. 3 is a view similar to Fig. 1, showing the tear-strip wound upon a key;

Fig. 4 is a cross sectional view taken on the line 4—4 of Fig. 3, looking in the direction of the arrows and on an enlarged scale;

Fig. 5 is an enlarged fragmentary top plan view, showing the free end of the tongue;

Fig. 6 is an enlarged fragmentary cross sectional view taken on the line 6—6 of Fig. 5;

Fig. 7 is a cross sectional view taken on the line 7—7 of Fig. 6, looking in the direction of the arrows;

Fig. 8 is a fragmentary cross sectional view on an enlarged scale, showing the tear-strip removed;

Fig. 9 is a side elevation of a modified form of key; and

Fig. 10 is a plan view of the tear tongue.

Containers, particularly cans such as commonly employed in packing fruits and vegetables, consist of a metal tubular shell and a bottom portion to which is secured the top in any approved manner, usually by seaming the top to the side wall of the container. These cans are usually opened by employing a can opener which cuts the metal on the top so as to give access to the interior of the can. This form of opening permits chips of metal and other foreign substances to pass into the can and thus contaminate the contents thereof. Some cans are opened by employing a tear-strip which is formed on the outer wall of the container. Such a tear-strip does not permit liquids to be packed for the reason that the tear-strip must be an appreciable distance down from the top of the can, and too large an air space would be left in the can. This type of can is usually employed for packing dried products, such as coffee, wherein a second band is used within the can and extends above where the tear-strip breaks off.

Applicants have devised an end for a can, which end piece may be employed with any standard form of can or container upon which the end may be secured and employs in its construction a tear-strip which when removed permits the end of the can to be lifted outwardly, leaving the level of the contents slightly below the top of the can and, at the same time, preventing any metal chips from falling into the can.

In referring to the drawing wherein is shown a preferred embodiment of our invention, we will assume that our improved end has been attached to an ordinary cylindrical tin can having a bottom therein and that the numeral 5 designates the side wall of the can; and it is here understood that the drawing is greatly exaggerated in order to illustrate the principle involved and that, in reality, the can, being made of thin sheet metal commonly employed in tin cans, would have quite a different appearance.

Our closure consists of a blank drawn so as to provide a depressed disc-like portion 6 surrounded by an annular wall 7 and having a flange 8, which is seamed to the side wall of the can as illustrated in Fig. 2. In this figure, it will be noted that this annular wall 7 telescopes into

the side wall of the can a short distance and that a scoring is provided at 9 and 11, which scoring permits this wall 7 to become a tear-strip, as will be later described.

Referring now to Fig. 7, it will be noted that a slot 12 is formed through the wall 7, and through this slot the reduced end 13 of the tongue 14 is passed so as to lie outside the periphery of the telescoping portion, while the wide portion 16 of the tongue lies adjacent the inner periphery of the telescoping portion or annular wall 7. Solder 17 is sweated into the slot 12 so as to secure the end 13 of the tongue, seal the slot, and secure a portion of the inner end of the tongue, the purpose of which will be later seen.

Referring to Fig. 6, it will be now noted that the wide portion 16 of the tongue overlies the upper scoring. This feature permits the beading chuck and roller to pass over the tongue without any danger of breaking the scoring in the sealing operation.

In use, a forked key 18 is preferably employed, which key is positioned on top of the can, as illustrated in Fig. 4, the said key engaging the end of the tongue. By a tearing action the tongue is pulled away from its first soldered engagement, and then the tear-strip follows until the key has made a complete revolution of the top of the can, winding the tear-strip thereon, as illustrated in Figs. 3 and 4. As the key and the tear-strip contact the end of the can, it will be apparent that a very even winding of the tear-strip on the key will result, and, accordingly, a much better opening of the can results.

It is a well-known fact that many key cans cannot be conveniently opened for the reason that the tear-strip slips off of the convolutions on the key and becomes almost unmanageable for the average person.

If desired, we may use a modified key, as shown in Fig. 9, which will further assist in holding the tear-strip in a pancake-like coil.

When the tear-strip has been removed completely from around the can, a small portion of the solder will still hold the tear-strip to the

depressed portion 6. Therefore, the key and the depressed portion 6 may be raised or lifted from the can. If desired, the key may be fulcrumed against the edge of the can and the depressed portion given an upward tilt in assisting in the raising of the same.

It will thus be seen that we have produced a can which will accomplish all the objects above set forth.

10 It is to be understood that the form of our invention herewith shown and described is to be taken as a preferred example of the same and that various changes relative to the material, size, shape and arrangement of parts may be 15 resorted to without departing from the spirit of the invention or the scope of the subjoined claims.

Having thus described our invention, we claim:

1. In a closure for a container, an end piece 20 having a depressed portion telescoping into the end of the container, the telescoped portion being scored on its inner periphery to form a tear-strip, said tear-strip having an opening formed therethrough, and a tongue of substantially the same 25 width as the tear strip extending through said opening, the portion of said tongue lying within said depressed portion being wider than the portion lying outside said depressed portion and extending above the top edge of the tear-strip and overlying the scoring of the tear-strip nearest the end of the container.

2. In a closure for a container, an end piece 30 having a depressed portion telescoping into the end of the container, said telescoped portion being scored on its inner periphery to form a tear-strip, said tear-strip having an opening 35 formed therethrough, a tongue of substantially the same width as the tear-strip extending through said opening, the portion of said tongue lying within said depressed portion being wider than the portion lying outside said depressed portion, and extending above the top edge of the tear-strip and overlying the scoring of the tear-strip nearest the end of the container.
